UNITED STATES PATENT OFFICE.

JOHN THOMSON, OF NEW YORK, N. Y.

UNIVERSAL ELECTRIC FURNACE, COMBINED WITH MEANS FOR CONDENSING ZINC.

1,090,429.

Specification of Letters Patent. Patented Mar. 17, 1914.

Application filed June 7, 1913. Serial No. 772,219.

To all whom it may concern:

Be it known that I, JOHN THOMSON, a citizen of the United States, and a resident of the borough of Manhattan of the city 5 of New York, State of New York, have invented certain new and useful Improvements in Universal Electric Furnaces, Combined with Means for Condensing Zinc, of which the following is a specification, reference being made to the accompanying 10 drawings, forming a part hereof.

This invention relates to electro-metallurgy having particular reference to the production of zinc.

15 The objects thereof together with a description of the particular means for attaining the desired results, and such an elucidation of the general principles applicable thereto as will adequately disclose the invention will be concurrently pointed out in connection with the description of the accompanying drawings which are representative embodiments of the invention.

Figure 1 is a side elevation; Fig. 2 is a 25 transverse center section, for instance, such a section as is taken on the plane which includes line A; Fig. 3 is a longitudinal center section taken along the line B, except that the lower right hand quarter is viewed from 30 the vertical planes indicated by lines C or D; Fig. 4 is a top plan view from the left hand of its transverse center line, but is a horizontal section from the right hand side of said line, taken along the plane E; Fig. 5 is a partial horizontal section of a sump-plug, showing a modification; Fig. 6 is a 35 cross sectional view of the resistor, as such might appear if drawn into Fig. 2; and Figs. 7 and 8 represent respectively a half 40 cross section and partial side elevation of the aforesaid resistor when its sides, contiguous to the charge, are sheathed.

As shown in the drawings, this adaptation of the furnace is particularly intended 45 for the reduction of igneous oxid of zinc combined with carbon, when the inert residual of the reaction is of small amount and of an ashy or sintered character; for various sulfid or oxidized zinc or lead-zinc 50 ores having a considerable content of

gangue of such character as is capable of being fluidized, and it may also be readily modified for general ore-smelting or the fusion of metals.

To avoid explanatory statements which 55 would in fact be in the nature of repetitions, it is stated that this application is more or less correlated with several pending applications filed by the present applicant on January 2nd, 1913, and application bearing 60 Serial No. 739,795, which was filed on said date, is particularly cited. This application is also related to my applications bearing Serial Nos. 760,915 and 760,916, filed April 14th, 1913, and Serial No. 766,248, filed 65 May 8th, 1913.

First confining the description to the drawings as they appear, the decomposition of the charge is effected by heat derived by direct conduction or radiation or by both, 70 preferably from an electrically incited porous bed-resistor, such as is ordinarily formed from pieces of broken carbon. The longitudinally extending resistor, as H, is interpolated between carbon terminals, as 75 8, 8^a, provided with metallic electrodes 9, 9^a, the energizing circuit being denoted by I. In cross section it preferably simulates the form of a trapezoid, or in its entirety a rectangular prismoid whose base rests upon 80 a grating which, as here shown, is constituted of a series of spaced rods, as 10, spanning a longitudinal throat 12. Along the horizontal zone of the furnace occupied by the resistor there are no side walls, but housings or abutments, as 13, 13^a, are provided 85 at the ends of the furnace for incasing the terminals. A series of vertically but transversely extending refractory plates, as 14, 14^a, of a material non-conductive to electricity, are set along and at right angles to the sides of the resistor, in such manner that at least the inner edges thereof, 15, 15^a, correspond with the angles of said resistor. The stability of these plates is insured by 90 embedding their lower ends in the sloped tamped plating or floor, as 16, which slopes inwardly and downwardly toward the resistor and by interlocking bricks above, as 17.

In the base of the furnace beneath the overhead hamper or charge-receiving space just described, are a series of lateral condensing chambers, as J, which may be more or less filled with filter coke, as 18, or stacks of spaced diffusing plates, as 19, or various combinations of both, of which two are shown. Condensed zinc is collected from the lateral chambers in longitudinal sluices, as 20, 20^a, terminating in run-off spouts, as 21, 21^a. These sluices 20, 20^a, are shown as being located in the chamber, adjacent to the side walls of the condenser.

Between the inner edges 22, 22^a of the septas 23, 23^a, which form the condensing chambers, adequate space is provided for a sump 23^b. This sump extends along and as near to the grating as is possible, but is far enough below the grating to leave spaces of sufficient area, as 24, 24^a, through which the volatilized products of the reaction may freely flow laterally into the parallel side chambers 25, 25^a, from whence the condensers are supplied. This sump is tamped in place upon tiles or bricks, as 26, supported by a series of spaced pillars or blocks, as 27, preferably set to form a longitudinal channel or flue, as 28, and several transverse ports, as 29; the latter serving to connect the aforesaid central flue and the aforesaid parallel side chambers. Before forming the sump a generous layer of some unbound lubricant, say artificial or natural flake graphite or carborundum sand, as 30, is spread upon the upper surfaces of the bricks 26. The spouts of the sump are provided with suitable tap plugs, as 27, 27^a.

By forming the resistor with sloped sides greater stability is obtained; the fume and gas which enter it flow from top to bottom in a general horizontal direction thence deflect and traverse downwardly through different vertical zones and, when the reaction so consumes the charge as to form slope-like hollows, as 31, Fig. 6, gravitation of its particles will produce direct impingement upon the resistor, as indicated by the arrows a. By eliminating the side walls along the charge receiving space, the main upper portion of the furnace virtually becomes simply an open top or table, and when the charge is in place thereon the sides and top of the resistor are thereby completely inclosed or buried, as denoted by the broken lines 32, 32^a.

The functions of the plates 14, 14^a, are manifold, for example, they serve to avoid a direct or longitudinal flow of electricity through the charge; to support the bricks 17, whereby to prevent charge material from directly resting upon the apex of the resistor; as thrust members between the end housings, and also enable the operator to readily inclose one, several or all of the

outer and top openings, as by means of 65 bricks 33 denoted in dotted lines in Fig. 2. In this wise too the resistor may be inclosed when first starting the furnace to avoid air burning; moreover, various sections of a charge may be more or less exhausted between any pair of the plates. On the other hand, there may be instances when the said plates can be dispensed with.

When the charge is composed of igneous 75 oxid of zinc and carbon (ZnO+C) whose residue is usually of nominal amount, ashy, clinkery or sintery in character, this can be readily withdrawn from along any portion of the "table". Again, the charge material may be backed with free bricks or it can be 80 somewhat tamped from behind to maintain intimate contact with the resistor, if such a mode of operation is preferred.

By placing the sump under and in close juxtaposition to the broad base of the prismatic resistor, the residue if liquidized or any liberated metal, such as lead, is free to flow between the spaces of the grate-rods and thence downwardly into the sump, where it is continuously subjected both to direct 85 radiated heat and also to the heat conveyed by the flowing fume and gases, whose impinging temperature will be nearly if not quite equal to that of the interior of the resistor from whence they are derived. The above described slag-flow is denoted by arrows b and that of the volatilized products by arrows c. The particular object of elevating the sump above the bases of the condensing chambers and supporting it on 90 spaced pillars, also in providing the parallel spaces along its sides, is to effect circulation of the fume and gases, as indicated by arrows d, thus completely enveloping the structure with heat at a high temperature. 95 As a consequence of this the entire surface of the sump without and within, except only as to the conduction of the limited area of the supporting pillars, is subjected to a temperature which is practically as high and uniformly distributed as in the resistor itself. This is a feature of prime importance in that the residue is thereby not chilled, as by downward conduction of its heat into the brick-work of the furnace, nor is there an 100 excessive drain of radiated heat from the base of the resistor. In the construction of the sump it is important to use material impervious to leakage of its contents. There 105 is available in the art suitable material having characteristics which render it not subject to destructive attack from the slags of various ores or concentrates thereof. Usually such material is more or less inert, having a negligible coefficient of expansion or contraction, yet when a tamped structure is 110 closely bound with the brick-work of a furnace, which will ordinarily have a much

higher relative co-efficient of expansion or contraction, the latter may act to disrupt the former. This difficulty is avoided by separating the ends of the sump from its 5 spouts, as 34, Fig. 3, and also employing the aforesaid unbound layer 30 which is preferably of a lubricating material such as graphite. The result is that the bricks of the furnace may expand when heated and 10 contract when cooled without imparting detrimental tensile or compressive stresses to the sump.

As the collection of matter in the sump may proceed at various rates, variable according to the constituents and character of the charge, it is desirable to readily ascertain when the accumulation has reached such a volume as needs be removed. To this end the inclosing end blocks or plugs are pierced 20 or slotted to receive rods, as 35, and if formed of carbon or carborundum they may be left in place. The holes for these rods are located so as to readily determine about the maximum depth of residue desired, which 25 by manual operation may be indicated by sounding. If, however, the character of the slag is such as to be somewhat conductive of electricity, as would be the case if oxid or sulfid of iron were present, then two carbon 30 rods 35, 35^a, Fig. 5, set approximately parallel to each other, horizontally, may be employed whereby an indicative electric signal may be obtained when the rising bath 36 reaches the rods and thereby closes the circuit 35 as through the wires 37, 37^a.

The trapezoidal cross sectional form of resistor lends itself most readily to adaptation for special purposes. Thus, as shown in Fig. 6, the outer faces may be formed by 40 stacking pieces of carbon which are larger than the core, thereby realizing stability. Also, as the electrical resistance will be less along the sides than through the interior, the flow of current and consequent heat development will be greater along the reaction 45 zones. The angle of the sides is somewhat immaterial. That shown, 15°, appears to be quite adequate for stability of structure and yet is not sufficient to interfere with a free 50 downward precipitation of the residue, whether it be ashy or fluid.

In certain cases it may be preferable to prevent the charge from coming in direct contact with the resistor carbon. The 55 present design and construction is uniquely adaptable thereto, and a preferred mode of realizing such a condition is shown in Figs. 7 and 8. Thus shallow recesses, as 38, are formed in the plates in the sides nearest to 60 the resistor and these recesses are adapted to receive a series of horizontally spaced strips or rods, as 39, of a material immune to reaction, such as recrystallized carborundum (SiC). These strips may readily be set so

that each will slope downwardly and outwardly, whereby liquid residue will not collect at the openings. The emission of heat to the charge, when the latter is in physical contact with the front edges of the strips, is both by direct conduction as arrow *e*, and by 65 direct radiation from the inner carbon, through the spaces, as arrow *h*. The flow of the volatilized products of the reaction from the seats of reaction through the strip spaces and thence into the resistor carbon, is 70 indicated by arrow *i*, and the downward precipitation of the residue along the edges of the strips by arrow *n*, finally passing between the grate-bars to the sump, as arrow *b*. This structure forms in fact a strong rigid 75 cage into which, by removing the upper cover bricks 17, the carbon may be freely inserted. Moreover, it is particularly well adapted for carrying out the process of volatilization of ZnO when not combined with 80 carbon to primarily react, that is to say, the oxid fume would then pass into the resistor when reaction between the said fume and the incandescent carbon ensues, producing Zn+CO. Consequently, according to that 85 method, resistor reaction carbon would require to be renewed from time to time. This can readily be done, the need of which would be indicated by a change in or fluctuation of the normal circuit voltage. 95

While the accompanying drawings generally represent a reduction from working plans, various shifts and modifications may be made without evasion of the fundamental features of this design. For example, the 100 rectangular prismatic form of resistor may be compounded to operate in parallel or in series, and if the furnace were to be used for smelting other than zinkiferous ores or for the fusion of metals, the sump might then 105 be built directly in the throat while the spaces beneath and at the sides thereof may be heated either by fuel or a separate electric resistor. Again, in support of the title of "universal" applicability, it would only 110 be necessary to make a few changes in a furnace constructed according to the accompanying drawings to adapt it for, say, smelting copper or lead ores or to fuse metals such as brass or aluminum. For example, 115 if the charge and the reacting or melting effects are such that metallic fume is not produced, then the resistor may be sheathed with thin SiC plates without providing them with perforations or slots, and by filling the 120 condensing chambers, as with good non-conducting bricks, the sump would for several purposes be kept adequately hot. On the other hand, the space 28 beneath the sump 125 may be packed with broken carbon to connect with carbon terminals set in the ends of the furnace. In this wise there would still be provision for a comparatively full circula-

tion of fume or gases through the broken carbon, while, if required, additional heat could be intermittently or continuously imparted to the sump and its surroundings by 5 electrically energizing what might then be termed the sump-resistor. In conclusion it can be conservatively stated that a high thermal efficiency may be realized by the use of this furnace when employed for the various purposes herein mentioned.

What I claim is:

1. In an electric furnace, a resistor whose transverse form is trapezoidal, a supporting grating therefor and an underlying sump.
  2. In an electric furnace, a resistor whose transverse form is trapezoidal, the reacting smelting or melting effect taking place along or contiguous to a sloped side or both sloped sides thereof.
  3. An electric zinc furnace having supported on a grate a longitudinally extending resistor of trapezoidal cross section and a charge receiving floor which slopes downwardly toward the grate.
  4. An electric furnace having an open table, a resistor reposing thereon, abutments containing the terminals and an underlying sump.
  5. An electric furnace having an open table, a longitudinally extending resistor reposing thereon, a plurality of vertically and transversely extending spaced plates resting upon the table, abutments containing the terminals and an underlying sump.
  6. An electric furnace having a longitudinally extending carbon resistor whose transverse form is trapezoidal, the sloped sides thereof being protected with a refractory plating of material having a lesser electrical conductivity than the interposed carbon.
  7. In an electric zinc furnace, a porous carbon resistor having a surface thereof, which emits heat to the charge, plated with perforated or slotted refractory material immune to the reaction, the fume and gas passing through spaces in the plating, thence into the said resistor and finally to a condenser.
  8. In an electric furnace, a tamped receiving sump, disposed beneath a resistor, which said sump is supported upon pillars so arranged as to provide a plurality of free spaces under its bottom and along its sides.
  9. In an electric furnace, a tamped receiving sump, whose ends are severed from the spouts and whose bottom is separated from the brick-work by a layer of unbound lubricating material.
  10. In an electric furnace, a receiving sump having end inclosing blocks provided with refractory rods for ascertaining when the sump-charge should be removed.
  11. An electric zinc furnace comprising a resistor, a supporting grating therefor, a
- throat beneath the grating, a sump beneath 65 the throat, spaces surrounding the sump into which the volatilized products of the reaction must primarily flow and from whence the condensing system is supplied.
12. In an electric zinc furnace, a porous carbon resistor, a grating upon which the resistor rests, an underlying sump into and toward which the inert and volatile products of the reaction flow, side spaces paralleling the sump into which only fume and gas 75 are deflected, and a system of condensing chambers which receive the fume flowing from said spaces.
13. In an electric zinc furnace, a porous carbon resistor whose transverse form is 80 trapezoidal, its base resting upon a grating beneath which is a condensing system, the reaction proceeding at or contiguous to the slopes from whence the volatilized products enter the resistor in horizontal directions 85 thereafter deflecting and passing down to the grating in a plurality of distinct vertical zones.
14. In an electric zinc furnace, a resistor whose transverse form is trapezoidal, its 90 base resting upon a grating beneath which is a sump, the reaction proceeding at or contiguous to the slopes from whence the inert or metallic products, if fluidized, flow down along the outer surfaces of said slopes, 95 deflect through spaces in the grating and fall into the sump.
15. An electric furnace having a resistor trapezoidal in cross section, a charge-receiving floor sloping downwardly and inwardly along each side of the resistor, and a longitudinally-extending sump below the adjacent ends of the floor.
16. A combined electric furnace and fume condenser having a longitudinally-extending 105 resistor, an open charge-receiving table having end walls but no side walls that extend above the supporting surface of the table, the table being provided with a grating upon which the resistor rests, a sump under the 110 grating, and longitudinally-extending condensing chambers arranged upon opposite sides of the sump below the table and having therein sluices adjacent to the outer side walls of the condenser for receiving the 115 liquid metal.
17. In a combined zinc furnace and condenser, a resistor supported upon a grate of a charge-receiving table, a sump located below the resistor, and a condensing system 120 arranged below said table, the floor of the charge-receiving table sloping downwardly and inwardly toward the resistor, the condensing system having floor portions sloping downwardly and outwardly so that the 125 condensed liquid metal can flow into a receiving sluice arranged along a side of the interior of the condenser.

18. In a condensing system, a centrally-arranged longitudinally-extending sump, and condensing chambers arranged at the sides of said sump, the sump being supported on spaced pillars or blocks to provide a free passageway between the chambers both above and below the sump, the sump also being arranged so that the fumes entering

the condensing system can flow downwardly past both sides of the sump.
